MOTOR CONSTRUCTION

Robert E. Zwayer, Bryan, Ohio, assignor to Aro Equipment Corporation, Bryan, Ohio, a corporation of Ohio

Application November 9, 1954, Serial No. 467,717

6 Claims. (Cl. 121—84)

This invention relates generally to a motor construction, and more particularly to a reversible pneumatic motor of the rotary vane type.

The motor construction of the present invention may be employed in hoisting devices of the type employed for moving loads from one height level to another. Such hoisting devices generally utilize a reversible type motor having suitable controls for changing both the speed and the direction of driving rotation. During the practical operation of such hoists, the motor is not needed to effect lowering of the load, and lowering may be effected by gravity force alone, regulated by brake means. It will be apparent from the present invention that if some of the potential on the reverse side of the motor can be transferred to the forward side, while retaining sufficient motor power in reverse operation to drive an empty hoist chain downwardly at a reasonable speed, the motor can serve the hoist with substantially greater efficiency, thereby enabling the hoist to handle heavier loads at higher speeds.

It is a primary object of the present invention, therefore, to provide a pneumatic motor construction of the rotary vane type having substantially increased power in the forward or lifting direction of driving operation as compared to the performance of prior art constructions, wherein the gain in power in the forward or lifting direction is greater than the loss in power in the reverse or lowering direction.

It is another object to provide a reversible pneumatic motor of the rotary vane type having a compressed air inlet and a pair of ports comprising primary and secondary exhausts, wherein the primary exhaust is particularly positioned in unbalanced relation between the inlet and the secondary exhaust.

It is a further object to provide a motor construction of the type described, wherein the primary exhaust is unbalanced at an angle of up to about 28° off center.

With these and other objects in view, my invention consists in the construction, arrangement and combination of the various parts of my motor construction whereby the objects contemplated are obtained as hereinafter more fully set forth, pointed out in my claims and illustrated in the accompanying drawing, wherein:

Figure 1 is a side elevational view, partly in perspective, showing a pneumatic hoist device of the type in which the pneumatic motor construction of the present invention may be utilized;

Figure 2 is a fragmentary vertical sectional view of the construction of Figure 1, on an enlarged scale, showing details of construction of the pneumatic motor;

Figure 3 is another sectional view, on a further enlarged scale, taken substantially as indicated at the line 3—3 on Figure 2, showing the particular location of the primary exhaust as taught by the present invention;

Figures 4 and 5 are sectional views similar to Figure 3 illustrating other locations of the primary exhaust;

Figure 6 is a plot of horsepower, revolutions per min-

2

ute, and air consumption plotted against torque for both forward and reverse rotation of a pneumatic motor construction corresponding to Figure 3, wherein the primary exhaust is particularly located in offset relation at an angle of about 28° from center;

Figure 7 is another plot similar to Figure 6, for a motor construction corresponding to Figure 4, wherein the primary exhaust is particularly located in offset relation at an angle of about 13° from center; and

Figure 8 is another plot similar to Figures 6 and 7, for a motor construction corresponding to Figure 5, wherein the primary exhaust is in balanced arrangement in the manner of the prior art.

Referring now more particularly to Figures 1 to 3 of the drawing, I have used the reference numeral 10 to indicate the housing of a typical hoisting device in which the motor construction of the present invention may be employed. The housing 10 is of hollow form and encloses a stator 12 having a cylindrical bore therein defining a cylindrical internal surface surrounding a rotor 14 rotatably mounted on a motor shaft 16. The rotor 14 is formed with a plurality of radially extending vane slots 18 which serve to receive a corresponding plurality of radially outwardly slidable vanes 20. The vanes 20 move outwardly in the slots 18 in response to centrifugal forces when the rotor 14 is driven, and serve to effect continuous contacting engagement with the internal surface formed by the stator 12.

As best seen in Figure 3 of the drawing, the longitudinal axis of the bore of the stator 12 is eccentrically disposed relative to the coincident axes of the housing 10 and the rotor 14, in the conventional manner of pneumatic motor constructions. A lower portion of the outer cylindrical surface of the rotor 14 contactingly engages a complementary mating portion of the internal surface of the stator 12 to provide a bearing seat 22 therewith.

A sprocket and suitable step-down gearing having a ratio of about 20:1, not illustrated but of the general type shown and described in co-pending Shaff application Serial No. 381,319, filed September 21, 1953, having a common assignee with the present invention, serves to raise and lower a hoist chain 30 as the rotor 14 rotates in forward and reverse directions. A suspending hook 32 and a chain hook 34 are connected in the usual manner with the housing 10 and the chain 30, respectively, as shown in Figure 1.

Flexible elements 36 and 38 are suspended from the ends of a control lever 40, and serve to permit manual rotation of a rock shaft 42 for motor-forward or load "up" operation and motor-reverse or load "down" operation, respectively. The rock shaft 42 effects control actuation of a suitable air regulating valve and brake, not illustrated in detail herein but of the general type shown and described in co-pending Zwayer application Serial No. 490,968, filed February 28, 1955, having a common assignee with the present invention.

As best seen in Figure 2 of the drawing the motor shaft 16 is rotatably mounted in suitable bearings 44 and 46. A cover plate 48 is provided over the right hand end of the housing 10, as viewed in Figure 1, and serves to enclose the rotor 14 within the hoist housing. The plate 48 is adapted to be connected to a suitable source of air under pressure. The air supply delivered by the fitting 50 communicates through suitable air intake passageways (not shown) with a first air inlet port 52 and a second air inlet port 54. Flow through the air intake passageways is suitably regulated by the aforesaid air regulating valve to permit selective supply of air to either of the

ports 52 and 54 in response to manual rotation of the rock shaft 42.

The ports 52 and 54 are positioned at opposite sides of and closely adjacent the rotor-stator seat 22. When an incoming supply of air is admitted at the inlet port 52, it will be apparent that expansion of the compressed fluid will perform work against the operating surfaces of the vanes 20, and thereby effect a forward or clockwise rotation of the rotor 14, as indicated by the direction arrow 56 in Figure 3. Such clockwise rotation corresponds to the load "up" direction of movement of the chain 30. When air is alternatively admitted at the inlet port 54, it will be apparent that reverse or counterclockwise rotation of the rotor 14 will be effected, as indicated by the direction arrow 58, and such rotation corresponds to the load "down" direction of movement of the chain 30.

For purposes of reference, I have designated the longitudinal axial center line through the motor shaft 16 by the letter O. The radial line from the center O through the center of the port 52 has been designated as station A, and the similar line through the port 54 as station B. The vertical center line through the top of the motor construction has been designated as station C.

It is the particular location of a plurality of primary exhaust ports 60 which constitutes the essence of the primary invention. The radial line through the center of the primary exhaust ports 60 has been designated in Figure 3 as station D, and in Figures 4 and 5 as stations D' and D'', respectively. In Figure 3 the angle COD is equal to about 28°, in Figure 4 the angle COD' is equal to about 13°, and in Figure 5, the angle COD'' is equal to 0°.

The position of the primary exhaust 60 at station D'' in Figure 5 coincides with station C, and is that of a normally balanced reversible motor as conventionally employed by the prior art. Such location is at a point midway between stations A and B on the opposite side of the stator 12. Assuming that the port 52 at station A is employed as an air inlet and that the port 54 at station B is employed as a secondary exhaust, forward rotation of the rotor 14 will be effected when air is delivered. As the air acting on the extended vanes 20 effects forward or clockwise turning of the rotor 14, a certain volume of air will be trapped between adjacent vanes, as indicated at X. Because of the difference in the exposed area of the two adjacent vanes bounding the volume X, there is a force differential exerted by the air pressure which tends to continue rotation of the rotor 14 in a clockwise direction, and as it does so the volume X continuously expands in size until it reaches the point of exhaust at the midway station C—D''. As the rotor 14 continues to turn beyond the midway station, a quantity of air at exhaust pressure is trapped between the same pair of adjacent vanes as indicated at Y, and is compressed as the volume continuously decreases in size.

The compression volume Y communicates with the secondary exhaust port 54 at station B, where the entrapped air is permitted to escape to the atmosphere, thereby completing a pumping cycle for the volume bounded between the adjacent vanes. When the expansion volume X travels between stations A and C, the air entrapped between the adjacent vanes performs work on the rotor. When the compression volume Y travels between stations C and B, the rotor necessarily performs work on the air. Consequently, by shifting the primary exhaust location clockwise from station C, it is possible to lengthen that portion of the cycle during which the air does work on the rotor and correspondingly shorten that portion of the cycle during which the rotor must do work on the air. In this manner, it is possible for the motor construction of the present invention to provide greater power in its forward direction of rotation than in its reverse direction of rotation. Such an arrangement may be termed an unbalanced reversible motor.

I have found that the ratio of forward power to reverse

power is dependent upon the positive angle of off-set within the range of from greater than 0° to 28°, with a variation of a few degrees on either side of the upper 28° limit. In Figure 4 of the drawing, I have illustrated an angular displacement COD' of about 13°. The angular displacement COD of about 28° shown in Figure 3 represents the optimum location of the primary exhaust. The arrangements of Figures 4 and 5 are intended primarily for purposes of illustrating comparative performances.

As best seen in Figure 3 of the drawing, the area of communication between the air inlet ports 52 and 54 and the fluid volumes confined between the adjacent rotor vanes is increased by cut-away portions 62 and 64. In particular, the cut-away 64 approaches the primary exhaust 60 so as to provide a length of internal surface therebetween which is approximately equal to the circumferential spacing between the vanes in contact therewith, thereby preventing any substantial compression therebetween during forward operation. The size of the cut-away portions 62 and 64 shown in Figure 3 will, of course, vary depending upon the number of vanes and their circumferential separation, but the particular 28° angle of offset from center for the primary exhaust ports 60 is independent of the size and spacing of the vanes.

In Figures 6, 7, and 8, I have plotted various performance parameters to illustrate the comparative operation of the arrangements illustrated in Figures 3, 4, and 5, respectively. The graphs of Figures 6 to 8 include plots of H. P., R. P. M. and air consumption against torque, for both forward and reverse rotation of the various motor constructions. These graphs have been plotted from information obtained by dynamometer tests on each of three rotor cylinders corresponding to the primary exhaust locations of Figures 3 to 5. All other motor parts were maintained identical for the data-obtaining tests. The stator of Figure 3 provides the data of Figure 6, and stator of Figure 4 provides the data of Figure 7, and the stator of Figure 5 provides the data of Figure 8.

The following information can be derived from the graphs:

Parameter	0°	13°	28°
	Balanced	Unbalanced	Unbalanced
Max. H. P., Forward.....	1.09	1.25	1.46
Max. H. P., Reverse.....	1.09	.87	.78
Free Speed, Forward.....	3,800	4,300	5,150
Free Speed, Reverse.....	3,900	3,300	3,150
Air Consumption at Max. H. P., Forward.....	46	47.5	45
Cubic Ft. of Air per Developed H. P., Forward.....	42	38	31

It will be seen from the above table that a shift of 28° in the offset location of the primary exhaust serves to increase the maximum H. P. for rotation in a forward direction by 0.37, while the corresponding decrease in reverse H. P. is only 0.31. It is also apparent that the free speed forward for the same two cylinders has been increased by 1350 R. P. M. while the free speed reverse has been decreased only 750 R. P. M. A further advantage will be apparent in the increase in operating efficiency in a forward direction by comparing the value of 42 cu. ft. of air per developed H. P. for the balanced arrangement to only 31 cu. ft. of air per developed H. P. for the 28° offset arrangement.

It will be apparent that by shifting the primary exhaust ports 60 off-center to obtain the desired unbalanced power in forward and reverse operation, there has been a greater gain in power on the forward side than is lost on the reverse side. I have found that the optimum angle of displacement is that which is sufficient to effect a differential in H. P. in the forward and reverse directions which is very nearly equal to about 2:1. As will be apparent from the above tabulated data, the optimum

28° offset location provides the approximately 2:1 differential of 1.87.

Changes may be made in the construction and arrangement of the parts of my motor construction without departing from the real spirit and purpose of my invention, and it is my intention to cover by the claims any modified forms of structure or use of mechanical improvements which may be reasonably included within their scope.

What I claim as new and desire to obtain by Letters Patent of the United States is:

1. A reversible fluid motor comprising a stator having a bore defining a continuously curved internal surface, a rotor eccentrically disposed within said bore in bearing contact with said internal surface to define an elongated fluid chamber of symmetrically increasing cross section from a minimum area at the ends thereof to a maximum area midway therebetween, said stator having a pair of ports communicating with said chamber at opposite ends thereof closely adjacent said portion of rotor bearing contact, one of said ports providing an inlet during forward rotor rotation and a secondary exhaust during reverse rotor rotation and the other of said ports providing a secondary exhaust during forward rotor rotation and an inlet during reverse rotor rotation, and said stator having on only one side of said maximum chamber area a third port communicating with said chamber intermediate said pair of ports and closer to said other of said ports than to said one of said ports to provide the only primary exhaust from said chamber.

2. A reversible fluid motor comprising a stator having a bore defining a continuously curved internal surface, a rotor eccentrically disposed within said bore in bearing contact with said internal surface to define an elongated fluid chamber of symmetrically increasing cross section from a minimum area at the ends thereof to a maximum area midway therebetween, said stator having a pair of ports communicating with said chamber at opposite ends thereof closely adjacent said position of rotor bearing contact, one of said ports providing an inlet during forward rotor rotation and a secondary exhaust during reverse rotor rotation and the other of said ports providing a secondary exhaust during forward rotor rotation and an inlet during reverse rotor rotation, and said stator having on only one side of said maximum chamber area a third port communicating with said chamber intermediate said pair of ports and closer to said one of said ports than to said other to provide the only primary exhaust from said chamber, the location of said primary exhaust being sufficiently unbalanced to one side of said maximum chamber area to effect a differential in power in the forward and reverse directions substantially equal to 2 to 1.

3. A reversible fluid motor comprising a stator having a bore defining a continuously curved internal surface, a rotor eccentrically disposed within said bore in bearing contact with said internal surface to define an elongated fluid chamber of symmetrically increasing cross section from a minimum area at the ends thereof to a maximum area midway therebetween, said rotor having a plurality of circumferentially spaced vanes radially slidable to ef-

fect contact with said internal surface and divide said chamber into adjacent volumes, said stator having a pair of ports communicating with said chamber at opposite ends thereof closely adjacent said position of rotor bearing contact, one of said ports providing an inlet during forward rotor rotation and a secondary exhaust during reverse rotor rotation and the other of said ports providing a secondary exhaust during forward rotor rotation and an inlet during reverse rotor rotation, and said stator having on only one side of said maximum chamber area a third port communicating with said chamber intermediate said pair of ports and closer to said one of said ports than to said other to provide the only primary exhaust from said chamber, whereby that portion of said chamber wherein said adjacent volumes increase in size for expanding fluid from the inlet toward the area of maximum chamber cross section is of greater length during forward rotor rotation and of lesser length during reverse rotor rotation than the remaining portion wherein said adjacent volumes decrease in size for compressing fluid from the area of maximum chamber cross section to the secondary exhaust.

4. A reversible fluid motor comprising a stator having a cylindrical bore therein, a rotor of smaller diameter than said bore eccentrically disposed within said bore in contacting engagement with said stator to define a bearing seat and a partial annular chamber extending from one side of said seat to the other, said chamber being of minimum cross-sectional area at opposite ends thereof adjacent said seat and symmetrically increasing in cross section from each side of said seat to a maximum area directly opposite said seat, said stator having a pair of ports communicating with said chamber at opposite ends thereof closely adjacent said bearing seat, one of said ports providing an inlet during forward rotor rotation and a secondary exhaust during reverse rotor rotation and the other of said ports providing a secondary exhaust during forward rotor rotation and an inlet during reverse rotor rotation, and said stator having on only one side of said maximum chamber area a third port communicating with said chamber adjacent said area of maximum cross section and offset from said area of maximum cross section toward said one of said ports to provide the only primary exhaust from said chamber.

5. A reversible fluid motor according to claim 4, wherein in the offset location of said primary exhaust is at an angle with the axis of said rotor, formed between radii passing through said area of maximum cross section and said primary exhaust, of about 28°.

6. A reversible motor according to claim 4, wherein the offset location of said primary exhaust is at a positive angle with the axis of said rotor, formed between radii passing through said area of maximum cross section and said primary exhaust, of from greater than 0° up to about 28°.
